UNITED STATES PATENT OFFICE.

JAMES W. ARROWSMITH, OF MORRISTOWN, NEW JERSEY, ASSIGNOR TO ARROWSMITH MANUFACTURING COMPANY, A CORPORATION OF NEW JERSEY.

DEVICE FOR MEASURING THE FEET.

1,313,048.

Specification of Letters Patent. Patented Aug. 12, 1919.

Application filed October 4, 1918. Serial No. 256,801.

To all whom it may concern:

Be it known that I, JAMES W. ARROWSMITH, a citizen of the United States, and a resident of the city of Morristown, in the 5 county of Morris, State of New Jersey, have invented certain new and useful Improvements in Devices for Measuring the Feet, of which the following is a specification.

- 10 The improvements relate to devices for taking impressions of the foot, in order that the dimensions and conformation of the foot may be ascertained and recorded. They may be used however for any similar purpose to which they are adapted. The present improvements are in the nature of improvements in the apparatus shown and described in my co-pending application No. 63,754, of November 27, 1915.
- 20 The improvements are illustrated in the accompanying drawings, in which Figure 1 is a plan view of a foot printing device embodying them; Fig. 2 is a vertical cross-section substantially on the line 2—2 of Fig. 25 1; Fig. 3 is an underside view of the device with the bottom removed, on the plane of the line 3—3 of Fig. 2, showing the parts in a different position from the position of Figs. 1 and 2, and Fig. 4 is a vertical medial 30 cross-section of the device taken on the same line as Fig. 2, with the parts in printing position.

The box or casing in which the working parts of the device are mounted, consists of 35 a bottom A with sides B and C and ends D and E forming a receptacle with an open top. The ends are cut away as shown at D' so that on one side they are of the same height as the side B, and on the other the 40 same as the lower side C. A short cover F is hinged to the upper edge of the side B and rests at its ends on the edges of the ends D and E, in which position it is secured by a hook and eye G, or any other suitable fastening. The object of the cover is to protect the inking roller H and to prevent ink from soiling the hands or the clothing of 45 those using the device.

A longitudinal partition I extends from 50 end to end of the box and is secured to the ends D and E with its bottom edge slightly above the bottom A of the box, so that a slot is provided between these parts through 55 which the inking sheet J passes back and forth. In the upper edge of this partition is

set a tube K, preferably of metal, and this tube presents a smooth surface to the underside of the inking sheet and also acts as the usual ink distributor. If desired the bottom of the partition I may be so positioned 60 with respect to the bottom of the inking roller that it also acts in the same manner. The action of the inking roller and the sheet are similar to that of the ordinary ink pad and rubber stamp.

The inking roller H is mounted in the ends D and E and consists of a spindle H', preferably of metal, a body of felt or other absorbent material H² thereon and a cover of silk or other fabric H³. Ink is supplied 70 to this roller in any desired manner and is absorbed by the cover and the felt or other absorbent and given off to the underside of the ink-carrying sheet J as it passes thereover.

The ink-bearing sheet J has a metal selvage L at one edge, and to the ends of this are secured the ends of the spring M which is approximately in the form of the letter M, and has its medial part secured to 80 the front of the box inside and at the bottom by means of a metal sleeve N, through which the spring passes and which is fastened to the box. It will therefore be seen that when the sheet J is drawn over the top of the box 85 and the edge secured to the spring moves toward the roller, the spring M will be flexed and will place the sheet under tension, and that when the loops of the spring come in contact with the side B of the box the further movement of the sheet in that direction will be permitted only by the stretching thereof. It will also be apparent that as soon as the sheet is released the spring will draw it back to its normal inoperative position. In this manner a very simple, effective and dependable means for retracting the sheet and returning it to its housing, and also a means for placing it under tension is provided; and it will be apparent that the 90 operation not only causes an intimate contact between the portion of the sheet which makes the impression and the inking roller, but by stretching the sheet gives it a greater area, and therefore a greater ink receiving 95 surface and causes it to conform to the irregularities of the entire surface of the foot when the foot is pressed thereon. The outer edge of the sheet is provided with a strip of wood or other relatively rigid material O 100

110

and a finger strap P, from which depends a loop R adapted to engage a pin S on the exterior of the side C so that the sheet may be caught and held in printing position. Any 5 other means for holding it may be employed, as, for instance, means similar to those for holding the lower edge of the ordinary roller shades used in railway cars.

Between the ends D and E a table T is 10 mounted so that its underside is above the bottom of the box and the ink sheet J and its upper surface below the upper edges of the box, and on this table one or more sheets 15 of paper or the like U may be placed and supported for the purpose of taking impressions of the foot. It is not necessary that this particular arrangement of the ink bearing sheet, printing table, and box be employed, as any other arrangement, such as 20 that shown in my application referred to, will answer the purpose so long as it prevents the ink bearing sheet from coming in contact with the sheet to be printed, except when the foot is pressed against the former, 25 and the two are in printing relation. A heel stop V mounted at one end of the box enables the user to place his foot in exactly the right position for printing. This is important where a graduated chart is used 30 giving the length and width of the foot in terms of shoe numbers, or in any other case where the paper to be printed is ruled or otherwise marked to indicate the size or condition of the foot.

35 It will be observed that the ink bearing sheet J is not in contact with the roller H when the parts of the device are in their normal positions of non-use. This prevents the portion of the sheet which lies next to the 40 roller at this time from receiving too much ink and thereby causing an uneven impression. The construction and arrangement are such also that the sheet J may be drawn out and allowed to retract a few times in 45 order to obtain a satisfactory coating of ink on the under side. This is advisable when the machine is not frequently used. When the sheet J is drawn over the table T or permitted to move back to its position at rest 50 thereover the loop R acts as a stop to prevent the forward edge of the said sheet from being depressed to such an extent that it will come in contact with the table or the upper sheet thereon. The loop therefore performs 55 the double function of a stop and a detaining device for the sheet.

One of the advantageous features of construction of the present device resides in the 60 fact that the elastic ink bearing sheet is not secured to the inking roller and yet is so supported that it automatically passes over the roller and is inked thereby on moving to and from its position over the sheet to be printed. This construction is far better 65 than the ordinary shade roller construction

in which the sheet is secured to the inking roller and wound thereon. It enables the maker to use a roller of small diameter and therefore to make the box lower and more compact. It also provides for contact between the roller and the ink bearing sheet at different points. That is to say the same point on the roller comes in contact with different parts of the sheet, and the sheet being loose thereon, the roller may have a slight free rotary movement at the end of each backward movement of the sheet. This insures an even and full distribution of ink.

What I claim is:

1. The combination of a frame, an inking roller mounted to rotate therein, an inking sheet independently mounted therein, and means for causing the sheet to pass over the said roller automatically in one direction, said means constructed to permit movement 80 of said sheet in another direction, and means for manually moving said sheet in that direction against the pull of said automatic means.

2. The combination of a frame, an inking roller mounted to rotate therein, an inking sheet independently mounted therein, tension means for causing the sheet to pass over the said roller automatically in one direction, and hand operated means for causing the said sheet to pass over the roller in another direction against the tension of said automatic means.

3. The combination of a frame, an inking roller mounted to rotate therein, an inking sheet independently mounted therein, and means for causing the sheet to pass over the said roller automatically in one direction, 100 said means comprising a spring secured to the sheet and normally holding it in a retracted position.

4. The combination of a frame, an inking roller mounted to rotate therein, an inking sheet independently mounted therein, means for causing the sheet to pass over the said 110 roller automatically in one direction, said means comprising a spring secured to the sheet and normally holding it in a retracted position, and means for placing the said spring under tension.

5. The combination of a frame, an inking roller mounted to rotate therein, an inking sheet independently mounted therein, and means for causing the sheet to pass over the said roller automatically in one direction, 120 said means comprising a spring secured to the sheet and normally holding it in a retracted position, said spring being secured at one point in said frame and extending to and being connected with the sheet at a point 125 laterally removed therefrom.

6. The combination of a frame, an inking roller mounted to rotate therein, an inking sheet independently mounted therein, and means for causing the sheet to pass over the 130

- said roller automatically in one direction, said means comprising a spring secured to the sheet and normally holding it in a retracted position, said spring being secured 5 at one point in the box or holder and extending to and being connected with the sheet at points laterally removed therefrom.
7. The combination of a holder, an inking roller mounted to rotate therein, an ink bearing sheet mounted independently of said roller to reciprocate in said holder and to pass over said roller, means for placing the said sheet under tension during its movement in one direction and thereby causing it 10 to press against the roller, said means constructed to permit said sheet to lie free of the roller when not being acted upon by said means.
8. The combination of a holder, an inking roller mounted to rotate therein, an ink bearing sheet mounted independently of said roller to reciprocate in said holder and to pass over said roller, means for placing the said sheet under tension during its movement in one direction and thereby causing it 15 to press against the roller, and means for releasing said tension and removing the pressure between the sheet and the roller operated through the movement of the sheet in another direction.
9. The combination of a holder, an inking roller mounted to rotate therein, an ink bearing sheet mounted independently of said roller to reciprocate in said holder and 20 to pass over said roller, means for placing the said sheet under tension during its movement in one direction and thereby causing it to press against the roller, a support for sheets of paper or the like to be printed, and 25 a guide for the ink bearing sheet holding it out of contact with the sheet to be printed while moving thereover.
10. The combination of a supporting frame, an inking roller mounted to rotate therein, an ink-bearing sheet secured with a portion of its surface normally adjacent to but out of contact with said roller, means for supporting said portion independently of the roller and for moving the same into close contact therewith, placing the same under tension and moving the same over the surface of said roller.
11. The combination of a frame, an inking roller rotatably mounted thereon, an ink bearing sheet independently supported with a portion adjacent to said roller, and means for moving the said sheet in one direction over the said roller and simultaneously placing it under tension to cause it to press against said roller as it passes thereover 30 freely.
12. The combination of a supporting frame, an inking device mounted therein, an inking sheet mounted adjacent to said inking device and adapted to reciprocate thereover, automatic means for moving said inking sheet over the inking device in one direction, and means for moving the said sheet thereover in the opposite direction against the tension of the automatic means, said automatic means being yieldable to permit such movement of said sheet, and such movement bringing the sheet in close contact with the inking device as it passes thereover.

Witness my hand this 20th day of September, 1918, at the city of New York, in the county and State of New York.

JAMES W. ARROWSMITH.
